(57) **CLAIM**

The ornamental design for a capillary cartridge for electrophoresis, as shown and described.

DESCRIPTION

FIG. 1 is a front, top, and left side perspective view of a capillary cartridge for electrophoresis according to the design;

FIG. 2 is a rear, bottom, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a cross-sectional view taken along line 9-9 of FIG. 3.

The broken lines illustrate portions of the capillary cartridge for electrophoresis that form no part of the claimed design. The alternate long and short dash lines define unclaimed boundaries of the claimed design.
